SKI BINDING

Anfinn Refsdal, Lilleaker, near Oslo, Norway

Application March 28, 1938, Serial No. 198,569
In Norway August 15, 1936

3 Claims. (Cl. 280—11.35)

The present invention relates to a ski binding with rigid toe irons and heel strap, which is adapted to be used for slalom as well as for ordinary running.

5 Most known slalom bindings are unsuitable for ordinary ski running, as the front members of the heel strap are passed below the toe irons, so that the binding, as required for slalom, affords a greater resistance against the upwards movement 10 of the heel than desired for ordinary use.

In accordance with the present invention this drawback is avoided thereby that the heel strap is passed through channel shaped depressions extending along the inside of the vertical parts 15 of the toe irons, so that the front members of the heel strap will be located at least at the rear part of the toe irons below the sole of the boot, i. e. between the sole of the boot and the horizontal part of the toe irons.

20 In this manner the pivot points of the heel strap will be placed further forwards, whereby less resistance is made against the vertical movement of the heel when the binding is to be used for ordinary ski running.

25 When the binding is to be used for slalom the front members of the heel strap are passed in the known manner below special side lugs secured to the ski behind the toe iron.

For bindings in accordance with the present invention it is preferred to use toe irons provided 30 with channel shaped depressions along their vertical parts, said channel shaped depressions extending along the whole length of the toe iron or in some cases only along the rear part of the toe iron, the depressions or channels being provided 35 in the latter case with a forward opening through which the heel strap may be passed either forwards below the front part of the toe irons or inwards through a mortise hole or cross channel below the horizontal part of the toe iron.

40 In some cases the front ends of the heel strap may be secured to the toe irons in some suitable manner at the forward end of said channels.

Two embodiments of the invention are illustrated on the drawing, which shows in perspective 45 view a part of a ski, a heel strap and in

Fig. 1, a toe iron according to one embodiment of the invention, and in

Fig. 2 is a toe iron according to another embodiment of the invention.

50 1 (and 8) is the ski, and 2, 2' and 3, 3' the toe irons, which may be provided with clamps, brackets or the like (not shown) for gripping the boot sole and which may be secured to the ski in any suitable manner, such as for instance by means 55 of screws. 4 and 5 are steel wires or the like, forming the front members of the heel strap.

In accordance with the embodiment illustrated in Fig. 1 of the drawing the toe iron 2 has a channel shaped depression extending from the rear edge of the toe iron to slightly beyond the middle part thereof, the channel being open at its front end so that the wire 4 may be passed through the opening and passed in a substantially straight line to a suitable tightening device (not shown).

5 Although it is preferred to carry the channel as far forward as illustrated on the drawing, this 10 obviously is not absolutely necessary, as even a shorter channel will at least partly have the desired effect.

In accordance with the embodiment of the invention illustrated in Fig. 2 of the drawing the 15 channel shaped depressions 6, 6' extend along the whole length of toe irons 3 and 3', so that heel strap wire 5 will be located between the boot sole and the toe iron all the way to the front edge thereof. In this case the heel strap wire 20 as indicated on the drawing may be passed through a mortise hole 7 in the ski 8 immediately in front of the toe iron.

In some cases the mortise hole or a transverse channel for taking up the heel strap wire may be 25 placed farther back, so as to be located below the horizontal part of the toe irons.

Other embodiments of a ski binding according 30 to my invention and within the scope thereof will be readily apparent to an expert skilled in the art. The scope of my invention is therefore defined by the appended claims.

I claim:

1. In a ski binding of the type comprising rigid toe irons and a flexible heel strap secured to the 35 ski independently of said toe irons, the improvement consisting of a set of toe irons, each of said toe irons having along the inside of its lower vertical edge a channel for receiving said heel strap, said channel extending from the rear of said toe iron to at least midway between the rear and the front of said toe iron, said strap passing through said channel and along said toe iron in a substantially straight line.

2. A ski binding according to claim 1, wherein 40 there is an opening through the bottom of each of said toe irons at the front end of said channel.

3. In a ski binding of the type comprising rigid toe irons and a flexible heel strap secured to the 45 ski independently of said toe irons, the improvement consisting of a set of toe irons, each of said toe irons having along its lower vertical edge a channel for receiving said heel strap, said channel extending along the entire length of said lower vertical edge.

ANFINN REFSDAL.
